SLIDING FASTENER

William C. Levering, East Orange, N. J.

Application October 8, 1945, Serial No. 621,007

7 Claims. (Cl. 24—205)

1

My invention relates to sliding fasteners.

An important object of the invention is to provide a sliding fastener for use in connection with three or more sides.

A further object of the invention is to provide a slide that will thread three or more groups of interlocking links.

A further object of the invention is to provide a device of the above mentioned character which is simple in construction and positive and reliable in operation.

Other objects and advantages of the invention will be apparent during the course of the following description.

In the accompanying drawings forming a part of this application and in which like numerals are employed to designate like parts throughout the same,

Figure 1 is a perspective view of a sliding fastener embodying my invention.

Figure 2 is a perspective view of the groups of interlocking links.

Figure 3 is a transverse section taken on line 3—3 of Figure 1.

Figure 4 is a similar view taken on line 4—4 of Figure 1.

Figure 5 is a longitudinal section taken on line 5—5 of Figure 1.

Figure 6 is a horizontal section taken on line 6—6 of Figure 5.

Figure 7 is a perspective view of the slide.

Figure 8 is a perspective view of a slightly modified form of slide.

Figure 9 is a transverse section taken on line 9—9 of Figure 8.

In the drawings, wherein for the purpose of illustration are shown preferred embodiments of my invention, attention being called first to Figures 1 to 7, inclusive, the numeral 10 designates flexible sides of a case or folder, and the numeral 11 designates an inner flexible side or partition. Each side 10 is equipped with a group of interlocking spaced links 12. Each interlocking link 12 is provided at its outer end with a yoke, forming pairs of jaws 13, receiving therebetween a bead 14, and these jaws are pressed inwardly for clamping engagement with the bead. The bead 14 is formed upon a flexible strip or tape 15, arranged upon the inner face of the side 10, and secured thereto by cement or other suitable means. Each interlocking link 12 is provided near its free end with a spherical lug 16, upon one side thereof, and upon its opposite side with a spherical recess 17. Arranged between the groups of interlocking links 12 is a longitudinal group of

2

spaced double locking links 18. Each double interlocking link 18 is substantially T-shaped and includes an upper horizontal arm 19 and a depending vertical portion or shank 20. The horizontal portion 19 is provided near its free ends with spherically curved lugs 21, disposed upon one face of the same, and spherically curved recesses 22, disposed upon the opposite face of the same. Each depending portion 20 is provided at its lower end with a yoke including jaws 23, receiving a bead 24, and these jaws are pressed inwardly for clamping engagement with the bead 24. The bead 24 is carried by a strip or tape 25, which is attached to the intermediate side 11 by cement or other suitable means. The horizontal portion 19 is provided in its top with a transverse intermediate notch or groove 22', as shown.

The numeral 26 designates a slide. This slide has a straight portion 26', extending to one end thereof, and an enlarged portion 27', diverging toward its opposite end. The slide 26 has a tubular web 27. This tubular web has a longitudinal guide passage 28, straight in a horizontal plane, receiving the intermediate double interlocking links 18. This tubular web 27 forms with the slide guide passages 29 which converge horizontally toward the straight portion 26'. The guide passages 29 are diverged in a horizontal plane and lead into a tapered link threading portion 30 of the common straight guide passage 31. The slide is provided at its longitudinal edges with slots 32, extending from one end to the other, for the passage of the strips 15. The slide is also provided in its bottom with a longitudinal slot 33, extending to the opposite ends of the slide, for receiving the depending portions 20 of the intermediate double interlocking links. The slide 26 is provided upon its top with an internal guide rib 34, extending to the opposite ends of the slide 26 and arranged centrally within the passages 28 and 31. This guide rib enters the notches 22' of the interlocking links 18. The enlarged portion 27' of the slide is longitudinally curved in a vertical plane, and the passages 29 and the tapered passage portion 30 are longitudinally curved in a vertical plane.

The slide 26 is provided upon its top with a rib 34', having grooves 35, receiving jaws 36, carried by a handle or hand-grip 37.

50 The operation of the sliding fastener is as follows:

When the slide fastener 26 is moved longitudinally to the left, Figure 1, in the direction of its enlarged portion 27', the double intermediate interlocking links 18 enter the passage 28, while

the side interlocking links 12 enter the converging passages 28. The double interlocking links 18 and the side interlocking links 12 then enter the tapered portion 30 of the common guide passage 31. When passing through the passage 28 and the passage portion 30, the double interlocking links 18 have their upper or free ends spread or diverged, by virtue of the longitudinal curvature of the passage 28 and passage portion 30 in the vertical plane. When passing through link threading portion 30, the side interlocking links 12 have their free end spread or diverged by virtue of the horizontal curvature or divergence of the passage portion 30. The interlocking links 12 are staggered with relation to the interlocking links 18, and as the slide continues to move to the left, interlocking links 12 are threaded between the interlocking links 18, and the lugs 16 of the links 12 enter the recesses 22 of links 18, while lugs 21 enter the recesses 17. The links 12 and links 18 approach each other as they near the straight passage 31, and when these links are within the straight passage, they are parallel in close relation, and securely interlock. When locked, the links 12 and 18 are substantially horizontal, Figure 1. When the slide is moved in the reverse direction, the links 18 and 12 are unlocked, as is obvious.

In Figures 8 and 9, I have shown a modification of the invention. The same group of interlocking links 12 are employed but they are transversely inclined or angularly arranged and the strips 15 are also inclined and secured to the sides 10, which are inclined. The numeral 30' designates generally T-shaped double interlocking links, provided with an upper generally horizontal portion 31', having a rounded top edge 32. Each double locking link 30' has a depending portion or shank 32', the lower end of which is provided with a yoke having jaws 33, clamped upon the bead 24, carried by the strip 25, and secured to the intermediate side 11. The generally horizontal portion 31' is provided near its ends and upon opposite sides with spherically curved lugs 34, and spherically curved recesses 35, corresponding to the lugs and recesses 21 and 22.

The numeral 36 designates a slide, having a tubular web 37 at its forward or large end, forming a guide passage 38. This tubular web 37 forms with the converging sides of the slide inclined passages 39, leading into the tapered portion 40 of a common passage 41, corresponding to the passage portion 30 and common passage 31. The slide is provided in its bottom with slots 42, extending throughout its entire length, to receive the strips 15, and is also provided in its bottom with a slot 43 extending throughout its entire length to receive the depending portions 32'. The forward portion of the slide 36 is curved longitudinally in a vertical plane, as described in connection with the first form of the invention. The rib 34 and notches 22' are omitted.

The operation of this device is similar to that of the first form of the invention.

It is to be understood that the forms of my invention herewith shown and described are to be taken as preferred examples of the same, and that various changes in the shape, size and arrangement of parts may be resorted to without departing from the spirit of my invention or the scope of the subjoined claims.

Having thus described my invention, what I claim is:

- 4
1. A sliding fastener, comprising an intermediate group of spaced double interlocking links, each double link having spaced ends, a flexible strip carrying the links, outer groups of spaced interlocking links for engagement with the spaced ends of the double interlocking links, flexible strips carrying the outer groups of interlocking links, and a slide common to all groups of links for engagement with all of such groups and having a tubular web forming a passage for receiving the intermediate group of double interlocking links and converging side passages, the slide having a common link-closing passage provided with a tapered portion in communication with the side passages, the outer groups of interlocking links being received by the side passages and conducted thereby into the link-closing passage.
2. A slide fastener, comprising an intermediate group of spaced double interlocking links, each double link having opposed ends, a flexible strip carrying the links, outer groups of spaced interlocking links for engagement with the opposed ends of the double interlocking links, flexible strips carrying the outer groups of interlocking links, and a slide common to all groups of links for engagement therewith and having a tubular web forming a passage for receiving the intermediate group of double interlocking links and converging side passages, the slide having a common link-closing passage provided with a tapered portion in communication with the side passages, the slide being curved longitudinally in a substantially vertical plane within the area of the double link receiving passage and the tapered portion of the link-closing passage, the outer groups of interlocking links being received by the side passages and conducted thereby into the link-closing passage.
3. A sliding fastener, comprising an intermediate group of spaced double interlocking links, each link being provided with a top having opposed ends and having a notch arranged between the opposed ends, a flexible strip carrying the links, outer groups of spaced interlocking links for coaction with the double interlocking links, flexible strips carrying the outer groups of interlocking links, and a slide common to all groups of links for engagement with all of such groups and having a tubular web forming a passage for receiving the intermediate group of double interlocking links, and converging side passages, the slide having a common link-closing passage provided with a tapered link threading portion in communication with the side passages, the slide being provided in its top with an internal longitudinal rib to enter the notches in the tops of the double interlocking links, the slide being longitudinally curved in the area of the double link receiving passage and the tapered link threading passage portion, the outer groups of interlocking links being received by the side passages and conducted thereby into the link-closing passage.
4. A sliding fastener, comprising an intermediate group of spaced T-shaped double interlocking links, each link including an upper horizontal portion and a depending shank, a flexible strip carrying the shanks, outer groups of spaced interlocking links for coaction with the double interlocking links, flexible strips carrying the outer groups of interlocking links, and a slide common to all groups of links for engagement with all of such groups and having a tubular web forming a passage for receiving the intermediate

group of double interlocking links, said slide being provided in its bottom with a longitudinal slot for receiving the shanks, said slide having converging side passages and a common link-closing passage provided with a tapered side link threading portion in communication with the side passages, said slide being provided in its edges with longitudinal slots receiving the strips carrying the side interlocking links, the slide being longitudinally curved in a vertical plane in the area of the double locking link receiving passage and the tapered link threading passage portion, the outer groups of links being received by the side passage and conducted thereby into the link-closing passage.

5. A slide fastener, comprising an intermediate group of spaced double interlocking links, each double link having opposed ends, a flexible strip carrying the links, outer groups of spaced interlocking links for engagement with the group of double interlocking links, flexible strips carrying the outer groups of interlocking links, and a single slide for engaging all of the groups of links for locking them together and having a tubular web forming a passage for receiving the double interlocking links, said slide having converging side passages and a common link-closing passage provided with a tapered link threading portion in communication with the side passages, all of said passages being substantially straight in a direction transversely of the slide, said slide being provided in its bottom with a longitudinal slot and having longitudinal slots in its edges, the slide being curved longitudinally in a substantially vertical plane within the area of the double link receiving passage and the tapered link threading passage portion, the outer groups of interlocking links being received by the side passage and conducted thereby into the link-closing passage.

6. A slide fastener, comprising an intermediate group of spaced double interlocking links, each link having opposed free ends, a flexible strip carrying the links, outer groups of spaced interlocking links for engagement with the opposed ends of double interlocking links, flexible

strips carrying the outer groups of interlocking links, and a slide having a tubular web forming a passage for receiving the intermediate group of double interlocking links, said slide having converging side passages which are transversely inclined and a common link-closing passage provided with a tapered link threading portion in communication with the side passages, the slide having a longitudinal slot in its bottom and longitudinal slots in its lower edges, the slide being longitudinally curved in the area of the double link receiving passage and the tapered link threading passage portion, the outer groups of interlocking links being received by the side passages and conducted thereby into the link-closing passage.

7. A sliding fastener, comprising a group of spaced interlocking links, each link having a plurality of lugs and recesses, a flexible strip carrying the group of interlocking links, a plurality of groups of interlocking links for engagement with the first group of interlocking links, each link of each of the last named groups having a lug and recess, flexible strips carrying the plurality of groups of interlocking links, and a slide common to all groups of links for engagement with all of such groups and having a tubular web forming a passage for receiving the first group of interlocking links and converging passages for receiving the plurality of groups of interlocking links, said slide having a common link closing passage provided with a tapered portion in communication with the converging passages.
